W. H. KRUEGER

AUTOMATIC RAZOR BLADE SHARPENER

Filed June 15, 1922

Patented Mar. 16, 1926.

1,576,518

UNITED STATES PATENT OFFICE.

WILLIAM H. KRUEGER, OF WILKES-BARRE, PENNSYLVANIA.

AUTOMATIC RAZOR-BLADE SHARPENER.

Application filed June 15, 1922. Serial No. 568,552.

To all whom it may concern:

Be it known that I, WILLIAM H. KRUEGER, a citizen of the United States, and residing at Wilkes-Barre, Luzerne County, State 5 of Pennsylvania, have invented certain new and useful Improvements in Automatic Razor-Blade Sharpeners, of which the following is a specification.

This invention relates to a stropping device intended particularly for use in stropping blades of safety razors.

The object of the invention is to provide a device of this character which can be permanently secured to a suitable support and 15 in which the guide frame through which the strop is drawn back and forth and which carries the holder for the blade to be sharpened, is free to move so that such guide frame will be free to change its position 20 depending upon the direction in which the strop is drawn through the frame. A further object is to provide a construction of this kind in which the spring for automatically rewinding the strop is so mounted 25 in the device as to be easily removable therefrom, thus permitting the replacement of a spring or the changing of the tension of the spring. A further object is to provide a strop lug or plate on the free end of the 30 strop which plate is so arranged as to engage a suitable part of the guide frame to limit the inward movement of the strop.

The foregoing and other useful objects 35 which will be apparent from the construction herein described are accomplished by means of the mechanism illustrated in the accompanying drawings in which:

Figure 1 is a side elevation of the device with certain parts appearing in section, this view being taken substantially on the line 1—1 of Figure 2;

Figure 2 is a plan view of the device, parts being shown in section;

Figure 3 is a longitudinal vertical sectional view on the line 3—3 of Figure 2; and

Figure 4 is a broken sectional view of a portion of the device.

Referring to the drawings in detail, the 50 numeral 10 indicates a bracket which is adapted to be rigidly secured in position on a suitable support. This bracket is provided with arms 11 in which a rod 12 is supported, the ends of this rod being threaded to receive nuts 13. Upon the rod 12 there is mounted a drum or casing, 14, preferably

cylindrical in shape, within which the strop is adapted to be wound, as hereinafter described. Each end of the casing 14 is provided with a cap or cover 15 which closely fit in the ends of the casing. Within the casing 14 a drum or barrel 16 is rotatably mounted on the rod 12, this drum being of a length sufficient to extend between the caps 15 of the casing. Into one end of the casing 14 there is inserted a spring cup or receptacle 17, this receptacle being constructed to closely fit within the casing in which it is held against rotation relative to the casing by means of an outwardly projecting stud 18, such as the head of a bolt or screw, which stud is adapted to engage a slot or groove 19 formed in the inner surface of the casing 14. It will be apparent that when the stud or lug 18 on the spring receptacle 17 is positioned within the groove 19 of the casing, the receptacle will be held against rotation relative to the casing.

Within the receptacle 17 there is arranged a coiled spring 20 the inner end of which 80 is secured to the drum 16 and the outer end to the wall of the receptacle 17. This spring is secured to the drum 16 by having the end thereof bent to form a hooked portion 21 which engages a groove 22 in the periphery 85 of the drum 16. If desired, however, the spring may be rigidly secured to the drum in any suitable manner, as by means of a set screw.

A strop 23 is also secured to the drum 90 16 in any suitable manner as by screws 24, the strop being arranged to be wound upon the drum as it is drawn into the casing by means of the action of the spring 20. It will be observed that the spring receptacle 95 17 is provided with a wall 17^a which projects inwardly from the periphery thereof and which forms a partition between the spring 20 and the strop 23. It will also be understood that the spring receptacle 17 is 100 removably mounted in the casing 14. This permits easy replacement of the spring 20 if the same becomes broken. It also enables the tension of the spring to be changed. For example, by detaching the stud 18 from the 105 slot 19 the receptacle 17 can be partially withdrawn from the drum without detaching the spring from the drum 16 and after being thus partially withdrawn the receptacle may be rotated one or more revolutions to tighten or loosen the spring as desired after which the stud 18 is again caused

to enter the slot 19. For thus withdrawing and rotating the receptacle 17 a suitable tool similar to a spanner wrench may be inserted in the holes 17^b in the receptacle.

6 Rigidly secured to the casing 14 is a suitable guide frame through which the strop is adapted to pass as it is drawn from, and into the casing. This frame comprises side members 25 which are permanently secured 10 to the casing 14 and which are held in rigid relation to each other by suitable rods such as 26. A shaft 27 is rotatably mounted in the guide frame between the members 25 thereof, the outer surface of this shaft preferably being roughened so that rotation of the same will be caused by frictional engagement of the strop therewith. Two of the rods 26 of the guide frame are so positioned as to hold the strop in frictional engagement 15 with the shaft 27 so that as the strop is drawn back and forth through the frame the shaft will be caused to rotate. In other words, two of the rods 26 and the shaft 27 are arranged in substantially the 20 same plane and the strop is passed through these rods and in engagement with the shaft so that the same will be bent out of a straight line and thus will frictionally engage and cause rotation of the shaft as it 25 is moved past the shaft.

A second shaft 28 is also rotatably supported in the guide frame parallel to the shaft 27 and a blade holder 29 is secured to the shaft 28. The shafts 27 and 28 are 30 provided with cooperating gear wheels 27^a and 28^a by which rotation of the shaft 28 is caused to take place when the shaft 27 is rotated by the movement of the strop back and forth through the guide frame. It will 35 be understood that the blade holder is so positioned that a blade mounted therein will be brought into contact with the strop first on one side and then on the other of the shaft 27 so that alternate sides of the blade will be acted upon by the strop as the same moves back and forth through the guide frame.

The free end of the strop 23 is provided 40 with a suitable handle 30 for operating the same. To limit the inward movement of the strop and the handle 30 attached thereto, there is provided a stop plate 31 which is secured to the strop in any suitable manner and which projects toward the guide frame. 45 Preferably, the stop plate 31 is formed by a

continuation of one side of a metal slip 32 by which the handle 30 is secured to the strop 23. The stop plate 31 is preferably slightly curved and extends over the surface of the strop. Two of the rods 26 of the 60 guide frame are so arranged as to be engaged by the stop plate 31 when the strop is drawn inwardly. The guide plate is so proportioned that it is capable of engaging over one of the rods 26 with the free end 65 thereof lying against the other of said rods.

Having thus described the invention what is claimed as new and desired to be secured by Letters Patent is:

1. In a stropping device, in combination, 70 a bracket adapted to be secured to a support, a rod mounted in said bracket, a casing supported on said rod, a spring receptacle removably and non-rotatably mounted in said casing, a drum rotatably mounted on 75 said rod and extending into said receptacle, a spring arranged in said receptacle and having one end connected to the receptacle and the other end connected to said drum, whereby a strop connected to said drum will 80 be automatically wound thereon when unwound therefrom, a guide frame rigidly secured to said casing, a blade holder pivotally mounted in said frame, and means operated by movement of a strop through said 85 guide frame for oscillating said holder.

2. In a stropping device, in combination, 90 a drum, a strop secured thereto and wound thereon, means for automatically rewinding the strop on said drum after it has been unwound therefrom, a guide frame through 95 which the strop is adapted to pass as it is drawn from said drum and rewound thereon, a blade holder pivotally supported in said frame, means operated by movement of 100 said strop for oscillating said blade holder, and means for limiting the inward movement of said strop as it is wound on said drum, said last named means comprising a stop plate secured to said strop adjacent the 105 free end thereof and extending over the surface thereof, a bar on said frame over which said plate is adapted to engage when the strop is drawn inwardly and a second bar on said frame against which the end of said plate is adapted to lie.

In testimony whereof I hereunto affix my signature.

WILLIAM H. KRUEGER.
